LATCHING MEANS

Sydney James Bickham, Oakville, Ontario, Canada, assignor to Orenda Limited, Toronto, Ontario, Canada
Filed June 22, 1967, Ser. No. 654,300
8 Claims. (Cl. 89—1.819)

ABSTRACT OF THE DISCLOSURE

In a missile launching system including a frame extending in the missile launching direction and a missile support element pivoted to the frame about a transverse axis, the missile support element being swingable from a normal supporting position to a limit position clear of the missile path, automatic latching means carried by the frame are operable by the swingable support element for positively retaining the latter when it has moved to the limit position. The latching means comprises a trip member in the form of a pivoted bell-crank, which is engaged by means carried on the support element for operating a latch bolt.

BACKGROUND OF THE INVENTION

(1) Field of invention

This invention relates to latching means and is concerned particularly with automatic latching mechanisms for use in a system comprising a stationary frame structure and an element which is movable relatively to the structure along a predetermined path to a limit position defined by a stop.

The invention is applicable to a missile launching system of the kind comprising a frame structure extending in the missile launching direction, a rear missile support, 35 a front missile support, which is pivoted to the frame structure so as to be swingable from a normal supporting position to a limit position at which it is clear of the missile path, and a latching mechanism for retaining the front support for preventing rebound of the latter when 40 it reaches the limit position.

(2) Description of prior art

The closest known prior art is No. 2,604,014, Walker et al., which discloses a missile launching system of the 45 kind referred to above. The latching mechanism is spring-operated, however.

Spring-operated latching mechanisms for use in apparatus having an element which is movable from a first, operative position to a second, latching position are well known. When the operational speed of the movable element is very high, however, it is not possible to construct a spring-operated latch which will react quickly enough to engage the movable element before the latter has rebounded from the limit stop. In the missile launching system with which the applicant is most concerned, the movable element to be retained has an extremely high operational speed, and a spring-operated latching mechanism as disclosed in the above mentioned patent would be quite unsuitable to retain the element.

SUMMARY OF THE INVENTION

The present invention provides an automatic latching mechanism which is operated by means carried by the movable element so that the speed of the latching operation is always in direct relationship to the operating speed of the element. The latching mechanism basically comprises a transverse pin mounted on the movable element and movable therewith, a latch bolt which is movable between a first, unlatching position and a second, latching position, the latch bolt when in its latching position extending across the path of movement of the pin and

2

being engageable therewith, a pivoted trip member having a first radial arm extending across the path of movement of the pin, and a second radial arm, and means providing a lost motion connection between the second radial arm and the latch bolt, the trip member being operable by engagement of the pin with the first radial arm to move the latch bolt into its second, latching position.

BRIEF DESCRIPTION OF THE DRAWINGS

One embodiment of the invention as applied to a missile launching system will now be described, by way of example, with reference to the accompanying drawings in which:

FIGURE 1 is a general perspective view of a missile launcher in which a latching mechanism in accordance with the invention is incorporated;

FIGURE 2 is an enlarged side elevation, in section, of the front missile support of the system shown in FIGURE 1, FIGURE 2 showing details of the latching mechanism; and

FIGURE 3 is a front elevation, partly in section, of a detail of FIGURE 2.

DESCRIPTION OF THE PREFERRED EMBODIMENT

Referring now to FIGURE 1, a missile 10 is supported by a launch beam 11 forming part of a stationary frame structure mounted on a trailer vehicle 12. The launch beam 11 is a tubular truss which is adjustable in elevation and train to lay the missile in launching attitude. Rear launch fittings or missile supports such as indicated at 13 support the tail end of the missile 10 and locate it. A front launch fitting or missile support 14 is pivotally located at the front end of the launch beam 11 and engages a cooperating portion (not shown) on the missile body. The missile support 14 is movable relatively to the stationary frame structure along a predetermined path, so that upon firing the support 14 swings forward and downwardly as the missile moves off the launcher, to a limit position shown in full lines in FIGURE 2, the limit position being defined by stop means 54 mounted on the stationary frame structure. The swingable missile support 14 is retained at the limit position by a latching mechanism 15.

Referring now more particularly to FIGURES 2 and 3, the launch beam 11 terminates at its forward end in a transversely angled end plate 16 which is welded thereto. Spaced-apart lugs 17 are welded to the end plate 16 and are bored to receive pins 18 for pivotally supporting the front missile support 14. The front missile support 14 comprises a hollow, welded sheet metal structure having at one end a sector-shaped cap 19 which engages a co-operating fitting (not shown) on the missile. The welded sheet metal structure diverges and is bifurcated to form two legs 20 each terminating in a solid pintle block 21. The pintle blocks 21 are adapted to receive the removable pivot pins 18 in threaded and locked engagement therewith in a well-known manner. An internal transverse plate 22 forms a crotch 23 between the legs 20 and also reinforces the structure of the support 14. The legs of the front missile support 14 are bored transversely, adjacent to the crotch 22, to receive coaxial tubular housings 24 welded in place. The housings have inner ends 25 which are angled to conform to the inner surfaces of the legs 20. The outer ends 26 of the housings are square and proud of the outer surfaces of the legs. The housings 24 each carry a composite resilient bush 27 comprising inner and outer metallic sleeves between which an elastomeric material is sandwiched, shock absorbing bushes of this type being well known in the art. The bushes 27 support a pin or shaft 28 which is retained therein and is also restrained

from rotation by roll-pins 29, which pass through bores in the outer ends of the pin 28 and the inner sleeves of the resilient bushes 27. A flat 30 is machined on the portion of the pin 28 exposed between the legs 20. Bolted to the end plate 16 of the launch beam 11 is an assembly consisting of an open-bottomed box bracket 31, a welded structure comprising a mounting plate 32, a top plate 33 and two side plates 34. One end of the top plate 33, remote from the mounting plate 32, is contoured to receive a cylindrical latch bolt housing 35 which is also welded to the side plates 34. The side plates have stiffeners 36 welded to their outer surfaces adjacent the lower edges. The latch bolt housing has a bore 37 in which a latch bolt 38 is slidably mounted for movement between a first, unlatching position, shown in ghost lines in FIGURE 2, and a second, latching position, shown in full lines in FIGURE 2. The latch bolt 38 has a lower end having a chamfered front face 39 and a rear flat face 40. The upper end of the latch bolt 38 is provided with a cap 41 secured by means of a bolt 42, the cap retaining a buffer ring 43 of resilient material. This construction limits the extension of the latch bolt on the lower end of its housing.

A spring-loaded ball catch 44 in threaded engagement in a bore in the upper end of the latch bolt housing 35, is adapted to engage a detent 45 in the latch bolt to releasably retain the latch bolt in its first, unlatching position. A rectangular slot 46 through the latch bolt is traversed by a pin 47 supported in bores through the sides of the slot, a co-operating slot 48 being formed in the wall of the bolt-housing and opening into a space 49 within the box bracket 31.

A trip member constituted by a bell crank lever 51 is pivotally mounted for movement about a transverse axis on a pin 52 passing through bores formed in the side walls 34 of the bracket 31. The bell crank lever has a first, lower, radial arm 53 which extends across the path of movement of the pin 28, and a second, upper, radial arm 50 which extends through slots 46 and 48 to engage the pin 47. The stop means 54, determining the limit position of the swingable supporting element 14, comprises a resilient buffer block bolted to the end plate 16 adjacent to its lower edge.

The operation of the latching means in the missile launching system will now be described.

With a missile mounted on the launcher, the front launch fitting 14 is in the "up" position as shown in FIG. 1, and the missile is located by its rear support fittings 13. The latch bolt 35 is manually withdrawn and is maintained in the unlatching position by ball catch 44. It is not essential that the bolt be set in this manner in order for the mechanism to operate, but in practice it is preferable to have the latch bolt cocked because of the accelerations involved. The bell-crank lever 51 will assume the position shown in ghost lines in FIG. 2.

When fired, the missile 10 moves very rapidly off the launcher and the front launch fitting 11 is caused to rotate to the downward position. The flat 30 on pin 28 clears the lower end of the latch bolt 38 but engages the lower radial arm 53 of the bell crank, thereby rotating it in an anti-clockwise direction as viewed in FIG. 2 until the front launch fitting is brought up against the stop formed by the buffer block 54. Rotation of the bell crank 51 is translated into downward movement of the latch bolt 38 through engagement of the upper radial arm 50 with the pin 47. The latch bolt extends to a latching position (shown in full lines in FIG. 2) where its flat surface 40 will engage the pin 28 as the launch fitting rebounds from the buffer block. The fitting is thereby prevented from further rotation on the rebound and possible contact with the rear of the missile body. The pin 28 will rebound from the flat surface 40 of the latch bolt, but the lost motion connection between the radial arm and the upper portion of the latch bolt prevents the additional mass of the bell crank lever from

immediately adding to the rebound forces acting on the latch bolt. Side forces are thus induced in the latch bolt which increase friction between it and its housing, to a degree that the momentum of the latch bolt is damped.

If the latch bolt is not set in the unlatching position before firing of the missile, the engagement of the pin 28 with the chamfered end surface 39 of the bolt will cause the latter to be urged upwardly into its housing to clear the flat 30 on the pin. Further rotation of the launch fitting will initiate the locking action already described.

The form of the invention hereinbefore described is given by way of example only, and it will be understood that the latching mechanism may be altered and adapted to many applications, other than missile launching systems, without departing from the spirit of the invention.

What I claim as my invention is:

1. In a system comprising a stationary structure and an element which is movable relatively to the structure along a predetermined path to a limit position defined by a stop means on the stationary structure, latching means comprising a transverse pin mounted on the movable element and movable therewith; a latch bolt; means mounting the latch bolt in the structure for movement between a first, unlatching position and a second, latching position, the latch bolt when in the latching position extending across the path of movement of the pin and being engageable therewith; a trip member carried by the structure, the trip member being pivoted about a transverse axis; the trip member having a first radial arm extending across the path of movement of the transverse pin, and a second radial arm; and means providing a lost motion connection between the second radial arm and the latch bolt, the trip member being operable by engagement of the pin with the first radial arm to move the latch bolt into its second, latching position.

2. Latching means according to claim 1, including a bolt housing carried by the stationary structure, the latch bolt being mounted in the bolt housing and slideable therein between its first and second positions.

3. Latching means according to claim 2, wherein the bolt housing includes a spring-loaded ball catch which cooperates with a detent in the latch bolt to retain the bolt in its first position.

4. Latching means according to claim 2, wherein the latch bolt has a chamfered front face engageable with the pin to permit movement of the pin past the bolt in the one direction towards the limit position.

5. In combination with a missile launching system including a frame structure and a missile supporting element pivoted to the frame structure about an axis which is transverse to the missile launching direction so that the supporting element is swingable along an arcuate path from a normal supporting position to an angularly spaced limit position; stop means mounted on the frame structure for determining the limit position, and latching means for positively retaining the support element in the limit position, the latching means comprising a pin mounted on the support element and extending transversely thereto, the pin being movable with the support element along an arcuate path; a latch bolt; means mounting the latch bolt on the frame structure for movement between a first, unlatching position and a second, latching position, the latch bolt when in the latching position extending across the path of movement of the pin and being engageable therewith; a trip member carried by the structure, the trip member being pivoted about a transverse axis, the trip member having a first radial arm extending across the path of movement of the transverse pin, and a second radial arm; and means providing a lost motion connection between the second radial arm and the latch bolt, the trip member being operable by engagement of the pin with the first radial arm to move the latch bolt into its second, latching position.

6. The combination claimed in claim 5, in which the latch bolt is slidable in a bolt housing mounted on the frame structure, the bolt housing including a spring-loaded ball catch which cooperates with a detent in the latch bolt to retain the bolt in its first position.

7. The combination claimed in claim 6, wherein the latch bolt has a chamfered front face engageable with the pin to permit movement of the pin past the bolt in the one direction towards the limit position.

8. The combination claimed in claim 5, wherein the ends of the transverse pin are retained in resilient bushes mounted in the missile supporting element, each

bush comprising inner and outer metallic sleeves with elastomeric material sandwiched therebetween, and means being provided to restrain the pin from rotation relative to the bushes.
